PUBLIC ADDRESS COMBINATION
UNIT OR THE LIKE

Charles R. Cresap, 21422 Rosedell Drive,
Saugus, Calif. 91601

Filed Aug. 16, 1972, Ser. No. 280,987

Term of patent 14 years

Int. Cl. D14—01

U.S. Cl. D26—14 L

Fig. 1

Fig. 2

FIG. 1 is a perspective view of an example of a public address unit or the like embodying the claimed design;

FIG. 2 is a rear elevational view thereof, omitting, for clarity only, the microphone and its cable and the carrying strap; and

FIG. 3 is a perspective view of the chassis portion thereof illustrating the rear (bottom, as viewed in FIG. 1) plate element and a pair of belt loops and their disposition thereon.

I claim:

The ornamental design for a public address combination unit or the like, substantially as shown and described.
